UNITED STATES PATENT OFFICE.

CHARLES WESLOW, OF NEWARK, NEW JERSEY.

GAME APPARATUS.

1,403,214.

Specification of Letters Patent. Patented Jan. 10, 1922.

Application filed March 5, 1919. Serial No. 280,710.

To all whom it may concern:

Be it known that I, CHARLES WESLOW, a citizen of the United States, residing in Newark, in the county of Essex and State 5 of New Jersey, have invented certain new and useful Improvements in Game Apparatus, of which the following is a specification.

My present invention relates to an improvement in toy projectile throwing devices and also relates to an arrangement including the improved projectile throwing devices and in which the improved projectile throwing devices find a special adaptation; and a principal feature of my invention is the employment of means for providing aerial trajectory for the projectiles by deflecting contact therewith after they are discharged by gravity from the 20 discharging or throwing device.

Another feature of my invention is the use of projectiles susceptible to magnetic attraction for the purpose of retrieving the projectiles by magnetic means after dis- 25 charge.

One of the main objects of the invention is to provide a combined projectile hurling device and projectile retrieving device adapted for use in toys and the like, in 30 which the direction the projectile is intended to take can with facility be controlled, a substantial force gathered by the projectile by extremely simple means, and the retrieving of the projectile accomplished 35 with great ease.

Another object of the invention is to provide a foldable case provided with a target frame by which the targets are secured, and which foldable case may be used for 40 containing the several elements of the game.

Still another object of the invention is to provide a supporting block attached to the projectile throwing implements and having a deflecting platform thereon.

And a still further object of the invention is to provide a telescopic member forming the projectile throwing device and comprising an outer tubular member pivotally connected to the supporting block and an 50 inner tubular member adapted to slide in the outer tubular member to which the retrieving means are secured, the telescopic member being provided to permit contracting of the same when it is desired to place 55 the same into the foldable case.

One of the advantages of my present embodiment of game shooter is that it may be made of standard tubing properly formed and of considerable length, the length of which enables the player to operate the device with facility either to actuate a projectile or to retrieve the same. 60

Another advantage of my device is that the greater the length of tubing used in the device described the greater the fall or 65 drop of the projectile, and therefore the greater the hitting power such projectile will have.

These and other features, capabilities and advantages of the invention will appear 70 from the subjoined detailed description of one specific embodiment thereof illustrated in the accompanying drawings in which—

Figure 1 shows in perspective the game ready for use with the projectile throwing 75 device in position for operation.

Fig. 2 is a plan view of the projectile throwing device.

Fig. 3 is an elevation mostly in section of the projectile throwing device. 80

Fig. 4 is an end view of the retrieving means of the projectile throwing device.

Fig. 5 is a fragmental perspective illustrating the path of movement the projectile will take when thrown by the throwing 85 device.

Fig. 6 is a fragmental perspective showing the projectile retrieving means.

In the embodiment shown my game comprises essentially a foldable case C in 90 which a target frame T may be set up, and a telescopic projectile hurling device P having at one end a supporting block S to be disposed in the case when the hurling device is ready for play and at the other end a 95 retrieving means R.

The case C comprises essentially two box sections 11 and 12 hinged to one another at abutting edges, forming one enlarged case when closed for containing the several 100 elements of the game and thus secure the same against loss and when opened forming two box sections with a partition between them. To the outer end of the section 11 there is pivotally connected the target frame T having end members 13 and shelves 14 which are adapted to be folded into the section 11. The end members 13 are provided with securing means 15 which are connected to said members 16 of the 110

section 11 to limit the outward movement of the frame T and to support the same in erect position when ready for use. To the edges of the shelves 14, targets comprising dolls D are pivotally connected.

The projectile hurling device P comprises essentially an outer tubular member 17 and an inner tubular member 18 slidably mounted in said outer tubular member. The 10 free end of the outer tubular member is provided with an enlarged block member 19 which is hingedly secured to the supporting block 20 on which is secured an extension 21 which forms a sight for aiming, the 15 upper face of which is in alignment with the face of the supporting block S and the block 19 being so hinged to said block S that the discharge end of the tubular member 17 will be directed to such upper faces of the 20 block S and extension 21. The extension 21 has part of it secured in a slot 26 formed in the block 20, adjacent to which an anvil 27 preferably composed of steel or the like is secured which forms a striking place on 25 which the projectiles strike when being discharged from the throwing device.

The inner tubular member 18 at its free end is provided with a block 22 surrounding the same and having a chamfered or countersunk portion 23 terminating at its end in alignment with the outer end of the tube 18, such chamfered portion 23 forming a mouth for the throwing device. At one side of the block 22, a magnet 24 of the horse 30 shoe type is secured having its active ends 35 projecting outward beyond the mouth or chamfered portion 23 of the block 22.

The tube 18 inside of the block 22 is provided with a lip 28 struck inwardly from 40 the tube proper which lip is resilient and formed to permit the introduction of projectiles in the tube 18 but to prevent the withdrawal or exit thereof from that end of the tube. On the tube 18 a distance from 45 the block 22 a trigger 29 is provided, the active end 30 of which is provided with an inner tooth 31 and an outer tooth 32 and extends into the tube 18 through the opening 33. The trigger 29 is pivotally connected 50 above the teeth 31 and 32 to the bracket 34 and has an elongated arm 35 which extends along the tube 18 and is normally spaced therefrom by the spring 36 connected to such arm 35 and the tube 18, the active end 55 30 thereby normally extending into the tube 18.

In the use of the device, assuming that the dolls have been raised, the block S for instance positioned in the section 12, the 60 tubular member P positioned relative to the block S, the projectiles 37 already introduced into the tube 18 through the mouth 28 and the first in order of discharge of the projectiles 37 anchored against discharge by 65 the active end 30 of the trigger 29, the de-

pression of the arm 35 against the tube 18 will raise the tooth 31 from the said first projectile and thereby permit the discharge thereof from the projectile hurling device. Upon raising such tooth 31, the other tooth 70 32 will be depressed to prevent the next projectile from being discharged and thereupon when the lever is released, the projectiles remaining in the tube 18 will be permitted to advance one projectile space and again anchor, the first one then in order of discharge being stopped by the tooth 31 which will then again be distended into the tube 18.

When retrieving the projectiles the inner 80 tube 18 is preferably drawn from the tube 17 and the magnet 24 brought adjacent to or into contact with the projectiles to pick up the same, the greater the length of the tube 18 the greater the facility with which 85 the projectiles may be picked up, the projectiles being of metal or material susceptible to magnetic attraction.

When the game is to be stored away, the tube 18 may be withdrawn from the tube 90 17 and placed into the case or if the tubes are short enough when drawn into one another to fit into the case, then merely the outer tube 18 moved into the tube 17 its farthest extent; thereupon the target frame 95 T swung into the case C; and the sections 11 and 12 swung toward one another in closed position.

It is obvious that various changes and modifications may be made to the details of 100 construction without departing from the general spirit of the invention, or exceeding the scope of the appended claims.

I claim:

1. In combination, an inclined hurling device having a point of release and a point 105 of discharge, said device being of adjustable length for varying the intensity of the hurling effort; and a releasing device mounted thereon.

2. In combination, a freely movable anvil; and a member constructed and adapted for free movement relative to a target and hinged to said anvil for projecting balls against the anvil and thence to the target.

3. In combination, a deflector; a member for guiding projectiles against said deflector; and a releasing device longitudinally adjustably secured to said member.

4. In combination, a target; a barrier; and a projectile hurling device longitudinally movable toward and from said barrier and held spaced from said target by said barrier when in position for hurling devices against the target.

5. In combination, sections secured together at their inner edges to form a single 125 closed box; and a target frame movably secured on one section at its outer edge and adapted thus securely to be contained with-

- in the box when the box is closed, and to be removed from the said inner edges and the outer edge of the other section when the sections are opened out in a common plane.
- 5 6. In combination, a hurling device comprising rigid telescoping members of adjustable inclination; and a releasing device mounted thereon.
7. In combination, a target, a block sliding relative to the target; and a member adjustably secured to said block for projecting balls against the block.
- 10 8. In combination, a block; a hard metal anvil embraced in the block and forming a portion of the top face of said block; and a member adjustably secured to said block for projecting balls against said anvil.
- 15 9. In combination, a supporting block; an anvil forming a portion of the top face of said block; and a tubular member having its forward end hinged to said block for projecting balls against said anvil.
- 20 10. In combination, a block; a block member having the lower edge of its forward end hinged to the rear upper edge of said block and provided with a longitudinal bore passing therethrough; and a tubular member having its forward end fixed in said bore.
- 25 11. In combination, a block provided with a longitudinal slot in its upper face; an aiming extension secured in said slot; a hard anvil in said slot and forming a portion of the top face of the block; a block member hinged to the block and provided with a bore passing therethrough and a tubular member having its forward end fixed in said bore.
- 30 12. In combination, a target; a barrier; a projectile hurling device comprising a rectangular supporting block adapted to be held spaced from said target by said barrier and provided with a longitudinal slot in its upper face; an aiming extension secured in said slot and pointing over said barrier; a hard steel anvil in said slot and forming a portion of the top face of said block near the middle thereof; a block member having the lower edge of its forward end hinged to the rear upper edge of said supporting block and provided with a longitudinal bore passing therethrough, a tubular member having its forward end fixed in said bore; and a releasing device for releasing balls in said tubular member.
- 35 55 13. In combination, a block; an extensible tubular member adjustably secured to said block; and a releasing device at an intermediate part of said tubular member.
- 40 60 14. In combination, a block; a forward tubular member hinged to said block; and a rear tubular member adjustably telescoped in said forward member and provided at its free end with an inwardly struck resilient lip to permit the introduction of balls there-
- 45 in but to prevent their extraction at said end; and a releasing device at an intermediate part of said rear tubular member.
- 50 15. In combination, a block; a forward tubular member secured to said block; a rear tubular member adjustably telescoped in 70 said forward member; a pair of spaced brackets outwardly struck from an intermediate part of said rear tubular member forming an opening therebetween; a trigger pivoted between said brackets and provided 75 with a rearwardly projecting arm extending along the tube and with an inner and an outer tooth projecting into said rear tubular member respectively forward and rear of the pivot point and spaced apart about the so-distance of one ball; and a spring for holding the forward tooth inmost.
- 55 16. In combination, a target; a barrier; a block adapted to rest against said barrier; a forward tubular member hinged to said 80 block; a rear tubular member adjustably telescoped in said forward member and provided at its free end with an inwardly struck resilient lip to permit the introduction of balls therein, but to prevent their extraction at said end; a pair of spaced brackets outwardly struck from an intermediate part of said rear tubular member forming an opening therebetween; a trigger pivoted 85 between said brackets and provided with a rearwardly projecting arm extending along the tube and with an inner and an outer tooth projecting into said rear tubular member respectively forward and rear of the pivot point and spaced apart about the distance of one ball; and a spring for holding the forward tooth inmost.
- 60 17. In combination, a target; a barrier; and a projectile hurling device adapted to be held spaced from said target by said 90 barrier and provided with an aiming extension pointing over said barrier.
- 65 18. In combination, a target section having a target therein; a barrier spaced therefrom; a projectile hurling device comprising 95 a supporting block adapted to be held spaced from said target by said barrier and provided with an aiming extension pointing over said barrier; and a guide member secured to said block.
- 70 19. In combination, a target section having targets therein; an aiming section; a barrier therebetween; a projectile hurling device comprising a supporting block adapted to rest in said aiming section and 100 while therein to be held spaced from said targets by said barrier and provided with a longitudinal slot in its upper face; an aiming extension secured in said slot and pointing over said barrier; a tubular member 105 hinged to said block; and a releasing device for releasing balls in said tubular member.
- 75 20. In combination, a block; a forward tubular member hinged to said block; a rear tubular member adjustably telescoped 110
- 80 115
- 85 120
- 90 125
- 95 130

in said forward member; and a ball-releasing device at an intermediate part of said rear tubular member.

21. In combination, a pair of box sections each having an open side and hinged together at their inner edges to form a single closed box adapted to open with the sections in the same plane thereby forming a barrier therebetween; and a target frame pivoted 10 in one section at its outer edge and adapted to be folded approximately perpendicular thereto or into the section for enclosing in said closed box.

22. In combination, a pair of box sections each having an open side and hinged together at their inner edges to form a single closed box adapted to open with the sections in the same plane thereby forming a target supporting section, an aiming section, a target 15 frame pivoted in the target supporting section at its outer edge and comprising a frame having shelves and dolls pivoted on the shelves; and adapted to be enclosed by said sections when the sections are closed together.

23. In combination, a pair of box sections each having an open side and hinged together to form a single closed box adapted to open with the sections in the same plane 30 thereby forming a target supporting section, an aiming section, and a barrier therebetween; a target frame pivoted in the target supporting section at the side opposite to said barrier and comprising a 35 frame having shelves and dolls pivoted on the shelves; and a projectile hurling device comprising a supporting block adapted to rest in said aiming section and while therein to be held spaced from said target frame 40 by said barrier.

24. In a game apparatus, in combination, a member for discharging projectiles by gravity therefrom, said member comprising a barrel and a magazine; projectiles for 45 loading said magazine and discharge from said barrel; means for loading said projectiles into said magazine and for preventing exit of the projectiles from the loading end of the magazine; means for aiming said barrel; a latch trigger for permitting discharge 50 of a projectile from the barrel and for retaining projectiles in said magazine and for retaining them therein during such discharge; and means comprising a flat surface 55 for providing aerial trajectory for the projectiles by deflecting contact of the projectiles therewith after discharge from said barrel.

25. In a game apparatus, in combination, 60 a member for discharging projectiles by gravity therefrom, said member comprising a barrel and a magazine, the magazine being detachable from the barrel; projectiles susceptible to magnetic attraction for loading 65 said magazine and discharge from said barrel.

rel; means for loading said projectiles into said magazine and for preventing exit of the projectiles from the loading end of the magazine; means for aiming said barrel; a latch trigger for permitting discharge of a projectile from the barrel and for retaining projectiles in said magazine and retaining them therein during such discharge; means operatively connected to the barrel and comprising a flat surface for providing aerial 75 trajectory for the projectiles by deflecting contact of the projectiles therewith after discharge from the barrel; and magnetic means comprised in said magazine for retrieving the projectiles after discharge. 80

26. In a device of the character described, a telescopic tubular member comprising an outer tubular member, an inner tubular member slidably mounted in said outer tubular member, the free end of one of the 85 said tubular members forming the discharging end of the device, a block surrounding the discharging end, a second block forming a striking platform to which said first named block is pivotally connected whereby the 90 tubular member may be moved to different angles relative to said second block.

27. In a device of the character described, a telescopic tubular member comprising an outer tubular member, an inner tubular 95 member slidably mounted in said outer tubular member, the free end of one of said tubular members forming the discharging end of the device, a block surrounding the discharging end, a second block forming a 100 striking platform to which said first named block is pivotally connected whereby the tubular member may be moved to different angles relative to said second block, and an anvil formed in said second block on which 105 the projectile strikes after discharging from said tubular member.

28. In a device of the character described, a telescopic tubular member comprising an outer tubular member, an inner tubular 110 member slidably mounted in said outer tubular member the free end of one of the said tubular members forming the discharging end of the device, a block surrounding the discharging end, a second block forming 115 a striking platform to which said first named block is pivotally connected whereby the tubular member may be moved to different angles relative to said second block, and an extension on said second block forming the 120 sight for the purpose of aiming.

29. In a device of the character described, a telescopic tubular member comprising an outer tubular member, an inner tubular member slidably mounted in said outer tubular member, the free end of said outer tubular member forming the discharging end of the device and being disposed at a lower level than the other end of said device when the device is positioned for discharging a 130

projectile, the free end of the inner tubular member forming the charging end of the same, the projectiles passing through the tube to gather momentum.

- 5 30. In a device of the character described, a telescopic tubular member comprising an outer tubular member, an inner tubular member slidably mounted in said outer tubular member, the free end of said outer tubular member forming the discharging end of the device and being disposed at a lower level than the other end of said device when the device is positioned for discharging the

projectile, the free end of the inner tubular member forming the charging end of the same, the projectiles passing through the tube to gather momentum, and an inwardly struck lip formed at the charging end of said inner tubular member, said lip being resilient and positioned to permit the introduction of projectiles but to prevent their exit from said charging end.
